Primary Examiner — Susan Bennett Hattan*Assistant Examiner* — Leanne Was(74) *Attorney, Agent, or Firm* — Norton Rose Fulbright US LLP(57) **CLAIM**

The ornamental design for a bottle, as shown and described.

DESCRIPTION

FIG. 1 is a front, right perspective view of a bottle showing my design;

FIG. 2 is a front elevation view of the bottle shown in FIG. 1; FIG. 3 is a back elevation view of the bottle shown in FIG. 1; FIG. 4 is a right side elevation view of the bottle shown in FIG. 1;

FIG. 5 is a left side elevation view of the bottle shown in FIG. 1;

FIG. 6 is a top plan view of the bottle shown in FIG. 1; and, FIG. 7 is a bottom plan view of the bottle shown in FIG. 1. The broken lines in FIGS. 1-7 depict portions of the bottle that form no part of the claimed design.

1 Claim, 5 Drawing Sheets---
